US0D1059363S

(12) **United States Design Patent** (10) **Patent No.:** **US D1,059,363 S**
(45) **Date of Patent:** **** Jan. 28, 2025**

(54) **DEVICE COVER**

(71) Applicant: **Amazon Technologies, Inc.**, Seattle, WA (US)

(72) Inventors: **Tim Wall**, Mill Valley, CA (US); **Jen-Yang Chang**, Kaohsiung (CN)

(73) Assignee: **Amazon Technologies, Inc.**, Seattle, WA (US)

(**) Term: **15 Years**

(21) Appl. No.: **29/817,158**

(22) Filed: **Nov. 29, 2021**

Related U.S. Application Data

(62) Division of application No. 29/765,019, filed on Jan. 5, 2021, now Pat. No. Des. 939,514, which is a division of application No. 29/661,335, filed on Aug. 27, 2018, now Pat. No. Des. 909,389.
